UNITED STATES PATENT OFFICE.

CALVERT B. COTTRELL, OF STONINGTON, CONNECTICUT.

GRIPPER MECHANISM FOR PRINTING - MACHINES.

SPECIFICATION forming part of Letters Patent No. 391,515, dated October 23, 1888.

Application filed October 11, 1887. Serial No. 251,994. (No model.)

To all whom it may concern:

Be it known that I, CALVERT B. COTTRELL, of Stonington, in the county of New London and State of Connecticut, have invented a new and useful Improvement in Gripper Mechanism for Printing-Machines, of which the following is a specification.

My invention relates to the grippers for taking the sheet, which are provided upon the cylinders of cylinder or drum printing-machines, and which, as the cylinder or drum rotates, carry the sheet forward between the cylinder or drum and the form upon the reciprocating bed of the press.

15 The object of my invention is to provide a very simple form of mechanism for positively and accurately operating these grippers in opening and closing; and to this end I combine with the series or set of grippers a gripper-shaft and toggle-lever or pair of toggle-levers, which serve to operate the grippers and to hold them closed securely by the middle joint of the levers coming to or passing a position in line with the other joints, and I employ a cam with 20 which a truck roll or pin upon the levers comes in contact as the cylinder rotates to shift the middle joint of the levers, and thus to close or release and open the grippers, and I also apply to the gripper-shaft or grippers a spring which 25 serves to accelerate their opening motion after they are released or relieved by the deflection of the toggle-levers.

The invention will be hereinafter more fully described, and pointed out in the claims.

35 In the accompanying drawings, Figure 1 represents a side elevation of such parts of a press as are necessary to illustrate my invention, including an end view of the cylinder or drum, and showing the gripper-operating mechanism 40 as in position to hold the grippers closed; and Fig. 2 is a plan of one end portion of the cylinder or drum and of the parts shown in Fig. 1. Fig. 3 is an elevation, partly in section, looking from the inner side of Fig. 1.

45 Similar letters of reference designate corresponding parts in all the figures.

A designates the cylinder or drum, which has its journals *a* supported, as is usual, in boxes *b* in the cylinder frames or uprights *B*.

50 C designates the feed-board.

The cylinder or drum *A* has the usual gripper-recesses, *a'*, in which is journaled the gri-

per-shaft *d*, having upon it the series or set of cylinder-grippers *d'*. These grippers close upon the receiving-edge *a'* of the press and operate to grasp the front end of the sheet and carry it forward with the cylinder between the cylinder and the form upon the reciprocating bed (not here shown) in a well-understood manner.

Upon the gripper shaft *d*, I have represented a pinion, *d²*, with which engages a sector, *D*, pivoted at *d³* upon one end of the cylinder. Obviously, by swinging the sector *D* in one or other direction upon its pivot, the grippers *d'* will be 65 opened or closed. With the sector is connected a toggle or a pair of toggle-levers, *D'D²*. These levers or members are pivoted together at *d⁴*, which forms the middle joint of the toggles, and the member or lever *D'* has a fixed pivot 70 at *d⁵*, while the member or lever *D²* is pivoted at *d⁶* to the sector *D*. Obviously, when the toggles are brought to a position in which the middle joint, *d⁴*, is in line with the pivots *d⁵ d⁶*, or is carried slightly past a position in line with 75 such pivots, as is illustrated in Fig. 1 by the dotted lines passing through the centers of the pivots *d⁵ d⁶*, the grippers *d'* will be held closed and cannot be opened, save by the deflection of the middle joint, *d⁴*, from such line. For the 80 purpose of opening and closing the grippers by deflecting the middle joint, *d⁴*, I employ a cam, *E*, here shown as secured to one of the side frames of the press, as shown in Fig. 2, and composed of two ribs or flanges, *e*, between 85 which is formed a channel, *e'*, receiving a truck-roll, *d⁷*, upon the member *D'* of the toggle. The cylinder rotates in the direction indicated by the arrow in Fig. 1, and at the entering end of the cam *E* there is a curved offset, *e^{*}*, which 90 serves to deflect the levers *D'D²* from a straight line, while at the opposite end of the cam is a similar curve or offset, *e^{**}*, which brings the levers back to or slightly past a straight line, and so closes the grippers *d'* and locks them in 95 closed position. The offset or curve *e^{*}* at the entering end of the cam will release or relieve the grippers and serve to open them; but for the purpose of giving them a quick action in opening, and completing their opening, I apply a spring to the gripper-shaft *d*, and this spring may be a spiral spring, *f*, applied as shown in Fig. 2.

It will be seen that the mechanism shown

will be very simple, and that by it I operate the grippers positively in opening and closing and locking them in their closed position.

What I claim as my invention, and desire to 5 secure by Letters Patent, is—

1. The combination, with the impression cylinder or drum and a set of cylinder-grippers and their shaft, of toggle-levers, whereby the grippers are operated and held closed by the 10 middle joint of the levers coming to or passing a position in line with the other joints, gearing between the toggle-levers and the gripper-shaft, and a cam whereby the toggle-levers are operated, substantially as herein 15 described.

2. The combination, with an impression cylinder or drum and a set of cylinder-grippers and their shaft, of a spring applied for throwing the grippers open, toggle-levers whereby the

grippers are operated in closing and are held 20 closed by the middle joint of the levers coming to or passing a position in line with their other joints, gearing between the toggle-levers and the gripper shaft, and a cam whereby the toggle-levers are operated, substantially 25 as herein described.

3. The combination, with the cylinder or drum and the gripper-shaft and grippers d d' , of the sector and pinion D D' , whereby the shaft is turned, the toggle-levers D' D' , connected with the sector, an opening spring, as 30 f , and the cam E , substantially as herein described.

CALVERT B. COTTRELL.
